UNITED STATES PATENT OFFICE.

FRED A. NEIDER, OF AUGUSTA, KENTUCKY.

HONING-SUPPORT FOR RAZOR-BLADES.

1,054,361.

Specification of Letters Patent.

Patented Feb. 25, 1913.

Application filed December 30, 1911. Serial No. 668,644.

To all whom it may concern:

Be it known that I, FRED A. NEIDER, a citizen of the United States of America, and resident of Augusta, county of Bracken, and 5 State of Kentucky, have invented certain new and useful Improvements in Honing-Supports for Razor-Blades, of which the following is a specification.

This invention relates to honing supports 10 for razor blades and has for an object to produce a support which is simple and cheap to manufacture and is simple and effective in operation. This and other objects I attain by means of a support embodying the 15 features herein described, and illustrated in the drawings accompanying and forming a part of this application.

In the drawings, Figure 1 is an end view 20 of a support embodying my invention and shown in connection with two safety razor blades which are in place in it. Figs. 2 and 3 are respectively top and bottom plan views of the apparatus illustrated in Fig. 1. Fig. 4 is a sectional view along line 4—4 of Fig. 2.

25 One of the principal features of my invention is to provide a honing support for razors, and particularly for safety razor blades, which will support the flexible blades throughout their entire length and will hold 30 them at a proper angle to the honing surface during the honing operation. This is accomplished by providing a support which is capable of receiving two blades and of simultaneously presenting them to the honing 35 surface.

The device illustrated as an embodiment 40 of my invention consists of a plate 5, which is provided near each lateral edge with means for holding a razor blade, and is so formed that one edge of each blade may be simultaneously presented to the hone and be held in the proper position for honing. The device is preferably so arranged that only 45 the edges of the blade, supported by it, contact with the honing surface during the honing operation. It is, however, so formed that a single blade may be honed at a time and will be held in the proper position on the hone.

50 As illustrated, the device consists of a thin but rigid metal plate, bent in any suitable manner along a line midway between its lateral edges, so that each lateral portion remains flat, or undistorted, but is inclined at such an angle to the other, that it 55 forms a support for the razor blade and will

hold the blade in the proper position during the honing operation.

Any suitable means may be employed for securing the blades in place on the support. 60 The means herein illustrated for securing each blade to the plate 5 consists of a tongue 6 and lugs 7, all of which are stamped from the metal of the plate. The lugs 7 are so located, that they will engage the apertures 65 usually provided in safety razor blades, when the blade is in place on the holder and will thereby prevent the blade from moving relatively to the holder. The lugs are preferably so positioned, that the razor 70 blade is held so that one of its cutting edges is substantially flush with one lateral edge of the plate. The tongue 6 is adapted to clamp or hold the blade into engagement with the lugs and also to hold it flat against 75 the lower face of one lateral portion of the plate, so that it is supported throughout its entire length by the relatively stiff plate. Each tongue is struck up from the metal of the plate, and is so bent that its lower 80 edge 8 extends slightly below the plane of the lower face of the portion of the plate from which it is struck, so that it normally stands in a position for receiving one cutting edge of the blade, and operates to yieldingly hold the blade against the adjacent face of the support. The spring action of the tongue can be varied by varying the length and width of the tongue, and its position, relatively to the lugs 7, may 85 also be varied, if desired. I find it most convenient to locate the tongue midway between the lugs 7 and so that its lower or free edge 8 is located a little above the line of the lugs 7, which coöperate with it. With 90 this arrangement, the tongue engages the central portion of the blade secured in place by it, and also simplifies the operation of locking a blade in place on the holder.

In locking a blade on the holder, the blade 100 is preferably held by its end edges between the thumb and finger and is bent transversely a small amount, so that the intermediate portion of one of its cutting edges can be introduced between the free edge 8 105 of the tongue 6 and the adjacent surface of the plate, while its ends are held clear of the lugs 7. After the edge of the blade has been introduced under the tongue 6, the blade is moved to such a position relatively 110 to the holder, that its end apertures will engage the lugs 7. The blade is then re-

leased and allowed to flatten out, due to its own resilience, so that it lies flat against the adjacent surface of the support. I find it convenient to cut away each end of the plate 5, as indicated at 9, so that the ends of the blades project beyond the ends of the plate, and are easily accessible during the operation of mounting a blade on the support, or of removing it from the support.

10 After two blades 10 have been secured to the support in the manner above described, the support is located on a honing surface, so that the lower cutting edges of the blades engage the honing surface, as illustrated in Fig. 1. Both blades may then be honed 15 simultaneously by sliding the support along the honing surface.

The operation of removing the blades is very simple. It consists in gripping the 20 end of the blade, to be removed, between the thumb and forefinger, bending the blade slightly, so as to lift its end apertures free of the lugs 7 and then withdrawing its edge from engagement with the tongue 6, while 25 the blade is held in the slightly distorted position. As soon as the edge of the blade is withdrawn from the tongue 6, the blade is entirely free of the support.

A single blade may be honed with the 30 support, by reason of the fact that the support is so formed that its lateral edges are flush with the edges of the blades in place upon it. This construction is also advantageous, since the relatively thin and flexible 35 blade is supported clear up to its cutting edge, and, consequently it is not subjected to any bending strains during the honing operation, and there is no tendency for it to bend, in case the honing support is held too 40 firmly against the hone. Another advantage of this construction, is that the blades always occupy the same angular position with relation to the honing surface, and, consequently the amount of the honing necessary is reduced to a minimum. It has 45 been found by experience that by using a device embodying my invention, the blades may be kept in excellent condition by periodically passing them over the hone, a few 50 times, and the honing operation is materially simplified. It will, of course, be understood that in honing a razor blade, the blade is turned over on the support, so that each side of each cutting edge is subjected 55 to the honing operation.

While the best results are obtained by

forming the blade holder as illustrated, that is, so that its lateral edges are flush with the edges of the blades during the honing operation, the construction may be varied, 60 so that the blades project a desired amount beyond the lateral edges of the holder, and, as has been said, various means may be employed for securing the blades in place on the holder. While I have shown the support formed on a plate which is capable of being bent or pressed to the proper contour, it will be understood that any other means may be employed which will provide 65 blade supporting portions, so arranged that the blades will extend at an angle to each other. The device may also be so constructed that it may be employed in honing blades of different sizes and kinds, but it is more particularly adapted for use with flexible 70 blades which need support throughout their 75 lengths.

Various other changes, modifications and substitutions may be made, without departing from the spirit and scope of my invention, as set forth in the appended claims.

What I claim is:

1. A honing support consisting of two plate-like members meeting each other at an obtuse angle and held rigidly at such 85 angle to each other, blade-supporting means upon each plate-like member and adapted to hold a blade upon each member with the outer edge of the blade projecting beyond the outer edge of such member.

2. A honing support consisting of a plate bent along a transverse line at an obtuse angle so that the lateral edges of the plate are adapted to support it upon a flat surface, and blade-supporting means upon the 95 underside of the plate and adapted to hold blades upon the underside of the plate with the edge of a blade projecting beyond each lateral edge of the plate.

3. A honing support consisting of a plate 10 bent at an obtuse angle along a line midway between its lateral edges, blade-supporting means upon the underside of the plate and consisting of lugs and tongues struck from the metal of the plate and adapted to hold a blade upon each side of said line and with an edge of a blade projecting beyond each lateral edge of the plate.

FRED A. NEIDER.
